Attorney -

UNITED STATES PATENT OFFICE.

GEORGE HENRY WOOD, OF OLDHAM, ENGLAND.

FASTENER FOR SPLIT STEEL LUBRICATING AND OTHER RINGS.

1,244,568.

Specification of Letters Patent. Patented Oct. 30, 1917.

Application filed February 18, 1917. Serial No. 149,106.

To all whom it may concern:

Be it known that I, GEORGE HENRY Wood, a subject of the King of Great Britain and Ireland, and resident of Oldham, county of Lancashire, England, have invented a certain new and useful Improvement in Fasteners for Split Steel Lubricating and other Rings, of which the following is a specification.

0 My invention relates to fasteners for split steel lubricating and other rings for shafting, pulley-boxes and the like, and the object of my invention is to produce by means of the improved fastener a ring which is perfectly circular, close fitting and easy to open and close.

The invention is illustrated by the accompanying sheet of drawings, in which:—

Figures 1 and 2 are respectively plan and elevation of a ring constructed in accordance with the invention, the ring being shown in its closed and locked position.

Fig. 3 is a fragmentary plan view, partly in section, drawn to an enlarged scale to show more clearly the locking of the free ends.

Fig. 4 is a similar view, but showing the free ends unlocked or open.

Fig. 5 is a front view of said Fig. 4. Like letters of reference indicate corresponding parts in the several figures.

In carrying out my invention, the free end *a* of the member *b*, which is hinged at *c*—Fig. 1—to the other member *d*, is provided in its width with a backwardly extending slot *e*—Figs. 2, 4 and 5—terminating in an inwardly sloping bevel *f* and with a pin *g* extending across said slot and at a slight distance from the bevel, said pin *g* taking in the jaws *h* in said free end *a* formed by the slot, while the abutting edge *i* of said free end *a* is cut radially from the center of the ring.

The free end of the member *d* is provided with a tongue *k* of a length and width corresponding to the slot in the free end *a* of the member *b*. This tongue *k* is formed with a

bevel *m*, and in the rear of said bevel *m* there is provided a semi-circular and transverse groove *n*, while the side extensions of 50 the tongue *k*, that is to say, the abutting edge *o* or end of the member *d*, are cut radially from the center of the ring.

With this arrangement of device it is only necessary to bring the free ends *a* and *d* together and exert slight pressure thereon, the tongue *k* of the member *d* by its bevel *m* riding over the pin *g* in the slot *e* of the member *a* and then springing down, engaging by its transverse and semi-circular 60 groove *n* said pin *g*—Fig. 3—and at the same time jamming the bevel portion *m* of the tongue *k* between the bevel portion *f* of the slot *e* and the pin *g* thereof, thus making a perfectly circular ring. 65

Slight pull on the free ends of the hinged members causes the forward edge of the semi-circular groove to ride up over the pin, instantly loosening the fastening.

Having now described my invention, what 70 I claim as new and desire to secure by Letters Patent of the United States is:—

A lubricating ring consisting of two hinged members provided with fastening means at their free ends, said means comprising a backwardly extending slot in one of the members terminating in an inwardly sloping bevel, and a pin extending across said slot, a tongue on the other hinged member having a beveled forward edge provided 80 with a groove to receive said pin, said tongue being of a length and width corresponding to said slot in the other member, and the abutting edges of the free ends of both of said members being cut radially from the 85 center of the ring.

In testimony whereof I have affixed my signature hereto this 15th day of January 1917.

GEORGE HENRY WOOD.
